SPARK PLUG

Charles F. Wahl, Wilmington, Del.

Application May 28, 1932. Serial No. 614,106

7 Claims. (Cl. 123—169)

This invention relates to improvements in spark plugs for internal combustion engines.

An object of the invention is to provide a spark plug of novel, inexpensive and advantageous construction in which the flow of current from the central electrode to the shell of the plug will be interrupted by a plurality of spark gaps for intensifying the spark and ensuring the ignition of the fuel gases; another object of the invention is to provide a novel and advantageous means for securing the electrodes within the porcelain core of the plug; and a further object of the invention is to provide a novel construction and arrangement of parts for the prevention of the fouling of the electrodes.

With the foregoing and related objects in view the invention resides in the elements and in the novel construction, combination and arrangement thereof hereinafter described and claimed.

In the accompanying drawing, illustrating the invention,

Figure 1 is a vertical section, enlarged, of a spark plug embodying the invention.

Figure 2 is a bottom view thereof.

Figure 3 is a transverse section through the insulating core, on line 3—3 of Fig. 1.

Figure 4 is a transverse section through the insulating core, on line 4—4 of Fig. 1.

Figure 5 is a bottom view of the insulating core

30 with the electrodes removed therefrom.

Referring to the drawing, 2 designates the metallic shell or casing of the plug and 5 the insulating core therein.

The lower portion of the shell 2 is exteriorly threaded, at 6, to permit it to be screwed into the usual threaded opening or bore in the wall of the combustion chamber of an engine, in the usual manner, and the central portion of the shell has a hexagonal flange 7 formed thereon to limit the movement of the shell when it is screwed into said opening or bore.

The lower end of the shell 2 is open for communication with the combustion chamber of an engine, and the upper end of the shell has a hollow head 8 formed thereon having a hexagonal exterior surface to receive a wrench for turning the plug.

The core 5 may be formed of porcelain or any other suitable insulating material and it comprises an elongated body having a centrally located, annular, expanded portion 9 within the head 8. The bottom of the expanded portion 9 is above an annular seat or shoulder 10 formed in the head 8, and the top of the portion 9 is below an unturned flange 11 formed on the upper end

of the head 8. A packing ring 12 is interposed between the shoulder 10 and the bottom of the expanded portion 9, and a packing ring 13 is interposed between the flange 11 and the top of the portion 9.

The packing rings 12 and 13 may be formed of copper or other suitable material which will form a tight joint and avoid breaking the porcelain or other material forming the core 5.

Before the shell 2, core 5 and rings 12 and 13 are assembled, the flange 11 stands up from the top of the head 8 and its interior diameter is equal to the exterior diameter of the expanded portion 9 of the core 5, and, after the portion 9 and rings 12 and 13 have been placed within the head 8, the metal forming the upstanding flange 11 is distorted and forced inwardly to the position shown in Fig. 1 to firmly clamp the portion 9 and rings 12 and 13 between the shoulder 10 and flange 11 and thus firmly lock the core 5 in place within the shell 2.

The core 5 has an upper part 14 which extends some distance above the head 8 of the shell 2, and it has a lower part 15 which extends from the expanded portion 9 thereof down through the shell 2, in spaced relation to the surrounding wall thereof, to and below the lower end of the shell; and the part 15 has an expanded free or lower end portion forming a head 16 which is located below or beyond the lower end of the shell 2 and in spaced relation thereto, as clearly shown in Fig. 1.

The core 5 has a longitudinal bore 17 extending axially therethrough and having an expanded upper end portion 18, and the main electrode 19 of the plug is located within this bore.

The main electrode comprises a wire 20 and a head 21 having an upwardly projecting stem 22 and a downwardly projecting stem 23. The upper end portion of the stem 23 is threaded and screwed into the threaded upper end portion of the expanded portion 18 of the bore 17. The lower end portion of the stem 23 is smaller in diameter than the threaded upper end portion thereof and it extends into the unthreaded lower portion of the expanded portion 18 of the bore 17, as illustrated in the drawing. The stem 23 has an axial bore therein which receives the upper end portion of the wire 20, and, after the wire 20 is soldered in the bore, opposite sides of the unthreaded lower portion of the stem 18 are indented, at 24, against the sides of the wire 20 therein as a means to prevent any liability of the separation of the stem and wire. The upper stem

22 is threaded for the reception of a suitable nut 25 for connecting a lead wire to the electrode.

Before the electrode 19 is placed within the bore 17, a suitable cement is introduced to the 5 same to cement the electrode therein.

One side of the shell 2 is provided with an 10 electrode 26 which extends downwardly from the bottom thereof. One end of the electrode 26 is firmly secured within a bore in the shell 2, and the other or free end portion 27 thereof 15 is bent or turned inwardly toward the axis of the plug.

The lower end portion of the main electrode 19 20 extends below the bottom of the head 16 and is bent, as shown in Figs. 1 and 2 to provide a free end portion 28 which is directed outwardly toward the inwardly turned portion 27 of the electrode 26 in alinement therewith, or substantially so, but spaced therefrom.

25 The side of the head 16 of the core 5 opposite to the electrode 26 is cut away or flattened, at 29, and the head 16 has a transverse bore 30 therein which extends from the flattened side thereof some distance into but not entirely through the head and which crosses the longitudinal bore 17 therein in spaced relation thereto; and the head 16 has a kerf 31 therein which 30 extends from the open end of the bore 30 to the lower or outer end of the head 16. The space between the opposing side walls of the kerf 31 is equal, or substantially equal, to the diameter of the bore 30.

35 The bore 30 is threaded for the reception of the threaded end portion 32 of an intermediate electrode 33 which has an angular bend 34 therein and which extends downwardly or outwardly from the bend 34 through and beyond the kerf 31 and has its free end located between but spaced from the end portions 27 and 28 of the electrodes 19 and 26, respectively, to provide two spark gaps 34 and 35.

40 The bend 34 in the electrode 33 is not made therein until after its threaded end portion 32 is screwed into the bore 30. Thus it will be understood that the production of the bend 34, after the end portion 32 of the wire forming the electrode has been screwed into the bore 30, will cause the wire to enter the kerf 31 and that thereafter the opposing side walls of the kerf will 45 prevent the unscrewing of the electrode 33 from within the bore 30. As an additional means to secure the electrode 33 within the bore 30 and kerf 31, a suitable cement is placed therein before the parts of the electrode are introduced thereto.

50 The provision of the head 16 on the part 15 of the core 5 and the location of the head 16 beyond the end of the shell 2 provides ample material in the core 5 within which to secure the intermediate electrode 33, and, at the same time, it permits the desired ample space between the part 15 of the core and the inner wall of the surrounding shell 2, for the prevention of the accumulation of carbon around the electrodes. The flattened side 29 of the head 16 also assists 55 in preventing the accumulation of carbon in the region of the electrodes.

60 The bottom or inner end of the shell 2 is beveled or inclined away from the head from the region of the electrode 26 to the opposite side of the shell 2, and this beveled or inclined end and its relation to the flattened side 29 of the head 16 provides the desired open space between the head 16 and the adjacent end of the shell while providing a suitably located support for the electrode 26.

The head 16 being considerably larger in diameter than the neck or part 15 of the core 5 which supports it is less likely to have the heat provided by the burning gases of the engine dissipated therefrom, so that it will remain quite hot at all times, during the running of the engine, and thus burn any lubricating oil which may find its way to the head. 80

I claim as my invention:

1. A spark plug comprising a metallic shell, and an insulating core secured therein and having a longitudinal bore and a threaded, transverse bore crossing the longitudinal bore in spaced relation thereto and having a kerf extending from one end of the transverse bore to the end of the core, a main electrode within the longitudinal bore and projecting from one end of the core, an electrode connected to and projecting from the shell, and an intermediate electrode having one end portion thereof threaded and screwed into said transverse bore and having the remaining portion thereof bent into said kerf and extended therefrom to a position between and spaced from the first named electrodes, the walls of said kerf preventing the threaded portion of the intermediate electrode from turning. 85 90 95 100

2. A spark plug comprising a metallic shell, an insulating core secured therein and having a part surrounded by and spaced from the wall of the shell and projecting beyond the end thereof and having an integral expanded free end portion forming a head beyond the end of the shell, said core having a longitudinal bore extending through the body and head thereof, said head having a transverse bore therein crossing the longitudinal bore in spaced relation thereto and a kerf extending from one end of the transverse bore to the outer end of the head, a main electrode within the longitudinal bore and projecting from said head, an electrode connected to and projecting from the shell, and an intermediate electrode having an angular bend therein and having one end portion thereof secured within the transverse bore and the other end portion thereof extending through and beyond said kerf to a position between and spaced from the first named electrodes. 105 110 115 120 125

3. A spark plug comprising a metallic shell, an insulating core secured therein and having a part surrounded by and spaced from the wall of the shell and projecting beyond the end thereof and having an expanded free end portion forming a head beyond the end of the shell, said core having a longitudinal bore extending through the body and head thereof, said head having a threaded, transverse bore therein crossing the longitudinal bore in spaced relation thereto and a kerf extending from one end of the transverse bore to the outer end of the head, a main electrode within the longitudinal bore and projecting from said head, and an intermediate electrode having one end portion thereof threaded and screwed into said transverse bore and having the remaining portion thereof bent into said kerf and extending therefrom to a position between and spaced from the first named electrodes, the walls of said kerf preventing the threaded portion of the intermediate electrode from turning. 130 135 140 145

4. A spark plug comprising a metallic shell, an insulating core secured therein and having a part surrounded by and spaced from the wall of the shell and projecting beyond the end thereof and having an integral expanded free end portion forming a head beyond the end of the shell, 150

5 a main electrode within the longitudinal bore and projecting from one end of the core, an electrode connected to and projecting from the shell, and an intermediate electrode having a bend therein and having one end portion thereof secured within said head and the other end portion thereof extending from said head to a position between and spaced from the first named electrodes.

10 5. A spark plug insulating core comprising an elongated body having an integral expanded portion forming a head on one end of the body and having a longitudinal bore extending through the body and the head thereof, for the reception of an electrode, said head having a threaded transverse bore therein crossing the longitudinal bore laterally thereof and having a kerf extending from one end of the transverse bore to the outer end of said head, said transverse bore and kerf being constructed to receive another electrode.

15 6. A spark plug comprising a metallic shell, an insulating core secured therein and having a bore extending longitudinally therethrough and having an expanded end portion, the outer end

portion of which is threaded, and a plurality of electrodes one of which is connected to the shell and one of which is located within said bore and comprises a head and a wire extending therefrom, said head having a stem extending therefrom and provided with a thread adjacent thereto screwed into the thread of the bore and provided with a free end portion smaller in diameter than the threaded portion thereof, said stem having an axial bore therein into which one end portion of said wire extends, and said free end portion being indented against said wire.

15 7. A spark plug electrode comprising a head and a wire extending therefrom, said head having a stem extending therefrom and provided with a thread adjacent thereto and having a free end portion smaller in diameter than the threaded portion thereof, said stem having an axial bore therein into which one end portion of said wire extends, and said free end portion being indented against said wire and thereby retaining it within said bore.
